UNITED STATES PATENT OFFICE.

ANSON E. SHUSTER, OF NORTH BEND, OREGON.

DEVICE FOR SUPPORTING UMBRELLAS AND THE LIKE.

No. 877,802.

Specification of Letters Patent.

Patented Jan. 28, 1908.

Application filed March 7, 1907. Serial No. 361,108.

To all whom it may concern:

Be it known that I, ANSON E. SHUSTER, a citizen of the United States, and a resident of North Bend, in the county of Coos and State 5 of Oregon, have invented a new and Improved Device for Supporting Umbrellas and the Like, of which the following is a full, clear, and exact description.

The invention is directed to improvements 10 in devices for supporting umbrellas and like articles from the body, and is constructed to enable the same to be carried in any desired position, as overhead, without the use of the hands or arms of the wearer.

15 The object of the invention, primarily, is to provide a device of this character, which when in use will be comfortable to the wearer, and to permit the umbrella or like article to be thrown in various angular positions 20 and positively retained or displaced with ease and facility.

Reference is to be had to the accompanying drawings forming a part of this specification, in which similar characters of reference 25 indicate corresponding parts in all the figures.

Figure 1 is a front elevation of the device as when in use; Fig. 2 is a side elevation of the same; Fig. 3 is a fragmentary side view 30 on an enlarged scale and partly in section; Fig. 4 is a cross section of the device taken centrally through the universal joint; Fig. 5 is a fragmentary, sectional view on an enlarged scale, and Fig. 6 is a face view of the 35 lower end of the collar and parts carried thereby, showing the pivot pin in section.

The preferred form of construction comprises a yoke 1, which is preferably made of very thin sheet metal shaped to exactly conform 40 to the shoulders of the wearer when in operative position. The yoke is provided with a downwardly-extending tongue 2, to which is secured in any suitable manner, preferably at the rear face thereof, a belt 3 designed 45 to pass about the waist of the wearer. Secured by screws 4^a or otherwise affixed to the front face of the tongue 2 on the longitudinal center thereof, is a T-shaped member comprising a ribbed stem 4 and a head 5, the latter being provided with an arc-shaped slot 6 arranged concentrically to a pivot pin 7, projecting from the lower end of the member 4.

As best shown in Fig. 4, the head 5 of the 55 T-shaped member is composed of two plates which are secured together by screws 8,

said plates being held slightly separated from each other by collars or bosses 9 interposed therebetween. This separation of the plates forming the head 5 provides for the 60 reception of the head of a screw 10, the body of which passes outwardly through the slot 6, and has threaded thereon a conical faced thumb-nut 11.

As best shown in Fig. 6, the pin 7 is 65 slightly reduced in diameter near its outer end for receiving and retaining the forked end of an arm 12, said arm being also preferably constructed with a strengthening rib and provided with countersunk notches 13 70 entering the opposite sides thereof near its upper end, these notches registering with the slot 6 formed in the head 5. By this construction it is obvious that on passing the body of the screw 10 in either of the notches 75 13 and tightening the thumb-nut 11, the arm 12 may be secured at any desired angle at the front of the yoke.

To the upper end of the arm 12 is rigidly fixed as by riveting as shown in Fig. 4, to 80 project outwardly at the front face thereof, a portion 14 of the stem carrying at its outer end one-half 15 of a ball socket. The opposite half 15^a of said socket is carried by the other portion 14^a of the stem and is 85 secured thereto by a transverse screw 16, a toe 17 being provided at the inner end of the portion 14^a of the stem in order that the diameter of the socket may be readily varied by the adjustment of said screw 16. Fitting 90 within the socket composed of the parts 15 and 15^a, and forming in connection therewith a ball and socket or universal joint, is a ball 18, said ball having an opening 19 passing centrally therethrough and flared 95 at both ends, as clearly shown in Fig. 4. This opening 19 receives a bolt 20 passing through elongated openings in the sides of the socket, and is provided with a thumb-nut 21 screwed on its threaded end, the 100 latter operating to contract the diameter of the socket and bind the ball therein when tightened.

On the outer end of the ball 18 is carried to extend in a direction at right angles to the 105 opening 19, a clamp, comprising a fixed jaw 22 and a movable jaw 23 hinged thereto on a pin at 24. Each of said jaws are formed with a semicircular opening, which is preferably provided with a rubber or other soft lining 25 for receiving and bindingly holding the staff of an umbrella or other like article, 110

the staff of an umbrella being represented between these jaws in Figs. 1, 2 and 3.

For forcibly holding the jaws 22 and 23 together, a lug 26 is extended at one side from each of them, one of said lugs being provided with a pin 27 on which is pivotally mounted a lever 28, the latter having a notch for receiving and engaging with a pin 29 carried by the opposite lug 26.

10 In the use of the invention, the yoke 1 is passed over the head and seated on the shoulders, with the tongue 2 extending downwardly in front of the body. The belt 3 is then adjusted about the waist, acting to 15 securely hold this end of the yoke in place. With the yoke in this position, the staff of an umbrella or other like device may be readily inserted between the clamping jaws, and the umbrella adjusted by means of the ball and 20 socket joint, together with the angular adjustment of the arm 12 to any desired position overhead, thus giving free use of the hands and arms while the umbrella is carried.

25 To remove the umbrella it is not necessary that the staff thereof be removed from the clamping jaws; but the same in connection with the ball and socket joint and the arm 12, may be bodily lifted from the pin 7 by 30 loosening the thumb-nut 11, leaving only the yoke and attached T-shaped member and the belt on the body. When again using the umbrella, it is only necessary to seat the arm 12 upon the pin 7 and re-secure it in 35 adjusted position by the thumb-nut 11.

Although I have described the preferred construction of my invention, I nevertheless regard the precise embodiment as not material provided the essential characteristics 40 are employed as pointed out in the annexed claims.

Having thus described my invention, I claim as new and desire to secure by Letters Patent:

45 1. In a device of the character described, in combination, a yoke, an arm pivotally connected to the yoke, means for securing said arm in adjusted position, a universal joint fixed to said arm, and a clamp fixed 50 to one member of said joint.

55 2. In a device of the character described, in combination, a yoke having a downwardly-extending tongue, a belt secured to said tongue, an arm pivoted to said tongue, means for holding said arm in varying angular positions, a universal joint fixed to said arm, and a clamp carried by one member of said joint.

60 3. In a device of the character described, in combination, a universal joint, a clamp fixed to one member of said joint, an arm by which said clamp is carried, and means for supporting said arm from the body.

4. In a device of the character described,

in combination, a support adapted to be 65 fixed to the body of a man, an arm pivoted to said support, means for holding said arm in varying angular positions, a universal joint carried by said arm, and a clamp carried by one member of said joint. 70

5. In a device of the character described, in combination, a yoke having a tongue, a belt secured to said tongue, a T-shaped member secured to said tongue having a slot in the head thereof, an arm pivoted to said 75 member, a screw working in said slot adapted to secure said arm in varying angular positions, a universal joint carried by the arm, and a clamp carried by one member of said joint. 80

6. In a device of the character described, in combination, a yoke having a tongue, a slotted member secured to said tongue, an arm pivotally supported on said tongue, a device operating in the slot of said member 85 adapted to secure said arm in varying angular positions, a universal joint carried by the arm, and a clamp carried by one member of said joint.

7. In a device of the character described, in combination, a support adapted to be fixed to the body of a man, a universal joint supported from said support, a clamp carried by one member of said joint, and means passing through said joint adapted to contract the socket thereof and hold said clamp 95 in varying angular positions.

8. In a device of the character described, in combination, a yoke, a ball and socket joint supported from said yoke, a clamp 100 carried by one member of said joint, and a bolt centrally passing through said joint having a nut adapted to contract the socket of the joint and hold said clamp in varying angular positions. 105

9. In a device of the character described, in combination, a yoke having a projecting pin, an arm having a forked end pivotally engaging the pin, means for holding said arm in varying angular positions, and a clamp 110 supported from said arm for the purpose described.

10. In a device of the character described, in combination, a yoke, an arm pivotally supported from the yoke having countersunk 115 notches at opposite sides thereof, a screw operating in a slot and having a conical thumb-nut adapted to engage with said notches, and a clamp carried by said arm, for the purpose described. 120

In testimony whereof I have signed my name to this specification in the presence of two subscribing witnesses.

ANSON E. SHUSTER.
